[57] ABSTRACT

A dual purpose projectile contains a high explosive shaped charge for use against materiel targets and a plurality of metal balls for use against personnel. An orifice plug is locked against a section of the projectile body to prevent the centrifugal release of the plug and the balls when it is desired to use the projectile solely in its anti-materiel mode. When the projectile is desired to be used against personnel targets and/or materiel the orifice plug is releasably retained only so long as the projectile is within the launching weapon.

FIG. 1

FIG. 3

FIG. 2

DUAL PURPOSE PROJECTILE

GOVERNMENTAL INTEREST

The invention described herein may be manufactured, used and licensed by or for the Government for governmental purposes without the payment to me of any royalty thereon.

BACKGROUND OF THE INVENTION

Various means have been used in the prior art to reduce the problem of troops having to carry a variety of projectiles in order to most efficiently attack and defeat different types of targets. One of the prior art problems with utilizing a variety of special purpose munitions to defeat different targets has been not only the cost of carrying additional supplies, but the loss of troop mobility and ability to maintain a prolonged offensive. Use of prior art special purpose devices creates logistic problems in determining the quantity and type of each ammunition to carry since the exact type of target one will encounter usually is not known.

SUMMARY OF THE INVENTION

The present invention relates to a dual purpose projectile which can be used to defeat materiel and personnel targets. The present invention utilizes a shaped charge to defeat a materiel or hard target, and alternatively a plurality of metal or steel balls as an anti-personnel munition. The present invention combines the effects of metered balls and a high explosive anti-tank shaped charge projectile in a single warhead.

An object of the present invention is to provide a dual purpose, anti-materiel, anti-personnel spin stabilized projectile.

Another object of the present invention is to provide a dual purpose spin stabilized projectile which reduces the logistic problems in determining the quantity and type of munition troops carry.

A further object of the present invention is to provide a dual purpose spin stabilized projectile which has increased offensive and defensive capability for the artillery and tank weapons.

For a better understanding of the present invention, together with other and further objects thereof, reference is made to the following descriptions taken in connection with the accompanying drawings.

BRIEF DESCRIPTION OF THE DRAWINGS

FIG. 1 is a diametral longitudinal cross-sectional view of the dual purpose projectile.

FIG. 2 is a partial plan view taken along line 2-2 of FIG. 1.

FIG. 3 is a partial cross-sectional view taken along line 3-3 of FIG. 2.

Throughout the following description like reference numerals are used to denote like parts of the drawings.

DESCRIPTION OF THE PREFERRED EMBODIMENTS

Referring now to FIG. 1 a projectile warhead 10 has a cylindrically shaped base 12 having a base rear end 14 and a threaded base front end 16. A rotating band 18 is peripherally positioned in base 12 intermediate rear end 14 and front end 16. A tracer assembly 20 is axially positioned in the base rear end 14. A hollow tubularly shaped body member 22 has an internally threaded body rear end 24 which is threadedly at-

tached to base front end 16 and an internally threaded body front end 26. A hollow ogivally shaped member 28 has an externally threaded ogive rear end 30 which is threadedly attached to tubular body rear end 26, and has a smaller tapered internally threaded ogive front end 32. A shaped charge assembly 34 is threadedly affixed to the ogive front end 32. The shaped charge assembly 34 comprises a nose cap 36 which holds a piezoelectric transducer 38 in its front end, an externally and internally threaded cylindrical support member 40 which is screwed to the ogive front end 32 and to the nose cap open end 42, and a conically shaped charge housing 44 fixedly positioned in counterbore 46. A fuze 48 is electrically connected to the output of transducer 38 by conductor 50 which is axially positioned in one end of charge housing 44, and a conically shaped copper cone 52 is fixedly positioned in the other end of the housing 44. A high explosive bursting charge 54 is retained in housing 44 intermediate fuze 48 and cone 52. The ogive member 28 has a plurality of transverse radially positioned ogive discharge bores 56 therein adjacent the ogive rear end 30. The bores 56 are releasably closed by orifice closing plugs 58. A detented collar 60, when it is in its closed anti-materiel position, prevents plugs 58 from being centrifugally ejected from bores 56. Steel balls 62, which are smaller in size than ogive discharge bores 56 and can pass therethrough, fill the intervening space between the space charge assembly 34, the ogive member 28, the body member 22 and the base front end 16.

Referring now to FIGS. 2 and 3, collar 60 is slidably positioned in a circumferential ogive collar groove 66, located in the rear end 30 of ogival member 28, adjacent to body front end 26. When the collar 60 is positioned in its anti-personnel mode, as shown in FIG. 2, a plurality of collar discharge bores 68 are axially aligned with orifice plugs 58. In this position collar 60 allows the plugs 68 and the balls 62, shown in FIG. 1, to be discharged when the projectile clears the launching weapon. A spring loaded detent assembly 70 located in ogival member 28 permits the collar 60 to be rotated so that it is either detented by first collar locking hole 72 or second hole 74. When the detent assembly 70 is located so that it is axial with first locking hole 72 the projectile is in its anti-personnel mode. When the detent assembly 70 is located so that it is axial with the second locking hole 72, the cover 60 covers the orifice closing plugs 58 thereby preventing discharge of balls 62 and thus placing the projectile in its anti-materiel mode. In the anti-materiel mode, maximum range is achieved because there is no loss in projectile weight with respect to range.

In operation the converging tapered cavity 64 inside the projectile body combined with the projectile spin causes balls 62, which may be metal, plastic, ceramic or any other suitable dense material, and may have non-cylindrical shape to flow toward the outer periphery of the cavity 64 to be discharged from the ogive discharge bores 56. When the projectile is used against personnel targets, the collar 60 is positioned as shown in FIGS. 2 and 3. After the orifice closing plugs 58 are discharged due to centrifugal force, caused by projectile spin, the balls 62 are disseminated at high velocity at a pre-determined and controlled rate to inflict casualties to personnel. Upon impact with a hard target the shape charge assembly 34 will function causing break up of the projectiles metal parts and cause the copper

cone 52 to be ejected as a high velocity molten jet stream. When the projectile is utilized for anti-materiel effects, the orifice closing plugs 58 are locked into place by collar 60. The plugs 58 prevent discharge of balls 62 and permit the projectile to achieve maximum possible range. On impact, the piezoelectric element 38 in the noz cap 36 functions the fuze 48. The fuze 48 detonates the bursting charge 54, causing the copper cone 52 to melt and penetrate the target.

The following disclosure and drawings are merely illustrative of the principles of this invention and are not to be interpreted in a limiting sense. I wish it to be understood that I do not desire to be limited to the exact details of construction shown and described for obvious modifications will occur to a person skilled in the art.

Having thus fully described the invention, what is claimed as new and desired to be secured by Letters Patent of the United States is:

1. A dual purpose projectile having both anti-materiel and anti-personnel capabilities comprising:
a base having a rear end and a threaded front end;
a hollow tubularly shaped body member having an internally threaded rear end and an internally threaded front end, the rear end of said body member threadedly attached to the front end of said base;
a hollow ogive member having an externally threaded rear end threadedly affixed to the front end of said body member, and a tapered internally threaded front end, the rear end of said ogive member having a plurality of radially positioned ogive discharge bores passing transversely through said ogive member, and a circumferentially positioned collar groove which communicates with said ogive discharge bores;
a plurality of orifice plugs releaseably positioned in said ogive discharge bores;
shaped charge assembly means attached to the front end of said ogive member for penetrating a materiel target upon impact of said projectile on said materiel target;
means for locking said plugs within said bores when said projectile is used in an anti-materiel mode, and for releasing said plugs during projectile spin when

said projectile is used in an anti-personnel mode; a plurality of balls contained within said body and ogive members intermediate said base and said shaped charge assembly means, said balls being capable of passing through the bores of said ogive member after said plugs have been ejected by the centrifugal force of said projectile spin when said projectile is in an anti-personnel mode.

2. A dual purpose projectile as recited in claim 1 wherein the shaped charge assembly means comprises: a cylindrically shaped support member having externally and internally threaded sections thereon and a counterbore therein, said support member being threadedly attached by the externally threaded section to the front end of said ogive member; a nose cap having an open rear end threadedly attached to the internally threaded section of said support member, and a front end; a piezoelectric transducer fixedly positioned to the front end of said nose cap; a conically shaped charge housing fixedly positioned in said counterbore; a fuze axially positioned in one end of said charge housing, said fuze being electrically connected to the output of said transducer; a conically shaped metal cone fixedly positioned in the other end of said charge housing; and an explosive bursting charge positioned intermediate said fuze and said cone.
3. A dual purpose projectile as recited in claim 1 wherein the means for locking comprises: a collar rotatably positioned in the groove around the rear end of said ogive member, said collar having a plurality of collar discharge bores therein and a first and second detent hole; and a spring loaded detent assembly means for locking said collar in said anti-personnel mode when said detent assembly means is located in alignment with said first detent hole and in said anti-materiel mode when said detent assembly means is located in alignment with said second detent hole.
4. A dual purpose projectile as recited in claim 1 wherein the balls are metal spheres.
